Primary Examiner — Kevin Rudzinski(74) *Attorney, Agent, or Firm* — Wood Herron & Evans LLP(57) **CLAIM**

The ornamental design for a display screen of a centrifuge with graphical user interface, as shown and described.

DESCRIPTION

FIG. 1 is a front view of a first embodiment of my new display screen of a centrifuge with graphical user interface design; and,

FIG. 2 is a front view of a second embodiment of the display screen of a centrifuge with graphical user interface shown in FIG. 1.

The rectangle shown in broken lines illustrates the display screen of a centrifuge. The words, symbols and numbers shown in broken lines illustrate unclaimed features of the graphical user interface applied thereto. The broken-line subject matter forms no part of the claimed design.
